X-RAY TUBE AND CATHODE STRUCTURE
THEREFOR

Norman C. Beese, Verona, N. J., assignor, by mesne assignments, to Westinghouse Electric and Manufacturing Company, East Pittsburgh, Pa., a corporation of Pennsylvania

Application July 12, 1933, Serial No. 680,013
Renewed January 22, 1937

12 Claims. (Cl. 250—35)

The invention is directed to an electron discharge device and especially to a novel type of cathode construction therefor. In one of its aspects the invention is specifically concerned 5 with a novel cathode construction and more particularly one that may be advantageously employed in a device such as an X-ray tube where a focal spot of predetermined configuration and size may be desirable and is sometimes a pre-
10 requisite.

An object of my invention is to provide improved X-ray tubes which may be readily produced and all of which may be employed to provide focal spots of the same and predetermined 15 dimensions.

Another object of my invention is to provide an improved cathode structure.

A further object of my invention is to provide an improved cathode structure which may be 20 manufactured at a moderate cost.

Other objects and advantages of my invention will be readily apparent from the following description and drawing wherein,

Figure 1 represents a longitudinal cross sectional view with some of the parts in elevation of an X-ray tube embodying my invention.

Figure 2 is a plan view taken on line II—II of Figure 1.

Figure 3 is a cross sectional view taken on 30 line III—III of Figure 2.

Figure 4 is a cross sectional view taken on line IV—IV of Figure 3.

As shown in Figure 1 the X-ray tube comprises a dielectric enclosing envelope 10 having 35 a reentrant tube 11 at one end and a reentrant tube (not shown) at the other end thereof. Extending in said last mentioned reentrant tube and sealed to said envelope is a copper anode 12 having a target of tungsten or the like embedded in 40 the free end thereof. The reentrant tube 11 has its free end in the form of a press 13 in which are sealed metallic supports 14, 15, 16 and 17. The supports 16 and 17 are electrically connected to a suitable cap 18 and serve as electrical conductors for the filament of the cathode structure, and the supports 14 and 15 merely serve as supporting means for the cathode structure. A metallic thimble 19 is secured to the conductor 17 and surrounds the press to protect the 50 press and upper part of the reentrant stem 11 from bombardment.

According to my invention the cathode structure comprises essentially a focusing device and a thermionically active body. The focusing device 55 comprises a metallic block 20 composed of

nickel-iron, molybdenum or the like. Extending along the entire length of said block is a groove 21, with sides thereof in cross section being in the form of arcs of a circle. The bottom portion 22 of the block has a slot 23 extending 5 from one end thereof to a point adjacent the other end thereof. The slot 23 is rectangular in cross section and has its upper end coincident with the lower end of groove 21 and its lower end coincident with the lower face of the bottom 10 22. The groove 21 and the slot 23 form a slot 15 extending to both the upper and lower faces of the block, a portion of the slot extending to two side limiting faces thereof and another portion to only one side limiting face thereof.

A thermionically active element 24 is located in the block 20. The element 24 is in the form of a coiled filament composed of tungsten or the like and has its ends depending in the direction of the depth of the slot 23. One end of the filament 24 is electrically secured by welding to a short length of a rigid metallic strap 25. The strap 25 is connected in like manner to the lower face of the bottom 22 so that the potential of the cup shall be approximately the same as that of 25 the filament.

The other end of the filament is secured by welding or other appropriate means to the upper end of the support 16. The so mounted filament or cathode 24 has its major axis parallel to the 30 longitudinal center line of the groove 21. The cathode 24 is so disposed that it is located centrally between the lower edges of the groove 21 and its central axis is substantially parallel to and in the horizontal plane of the lower edges of said 35 groove 21.

In the course of my experimentations with cathode structures adapted to be employed in X-ray tubes, I have found that the focal spots obtained on anodes of tubes of this character 40 may be of variable design depending upon the cathode structures employed. Since I desire to provide cathode structures which may be readily reproduced to provide the same type of focal spots of like pattern, my efforts were directed towards 45 the determination of the critical factors which must be known in order that the desired result might be accomplished.

Focal spot patterns that may be obtained may consist of a pair of spaced heavy lines between 50 which is located a light field containing therein a pair of lighter lines, a pair of heavy lines with a light area of substantially uniform intensity therebetween, or a pair of heavy lines with a lighter line adjacent and outside of each of said 55

heavy lines and a light area including all of said lines.

The size and energy distribution of the focal spot I have found may be controlled by controlling the width and depth of the groove 21, the width of the slot 23 and the distance that the filament is placed from the upper limit of the groove 21, the filament being disposed with its longitudinal axis parallel to the sides of the slot and 10 equally spaced therefrom and lying in the horizontal plane of said cup. In order that the focal spot, comprising a pair of parallelly spaced heavy lines between which is a lighter area of uniform intensity, may be obtained and which I prefer to 15 be produced in my X-ray tube, I have controlled the dimensions of the groove 21, the slot 23 and the distance between the filament and the upper limit of the groove 21. This result may be accomplished by having the upper width of the 20 groove 21 equal to about 5.8 to 6.0 millimeters, the depth of the groove 21 equal to 3.0 to 3.5 millimeters, the width of the slot 23 equal to 2.0 millimeters and the distance between the upper limit of the groove and the central longitudinal axis of 25 the filament equal to about 3.0 to 3.5 millimeters.

In order that a wider spot may be obtained, the width of the groove 21 may be equal to 7.0 millimeters, the depth of the groove 21 equal to .128 of an inch, the width of the slot 23 equal to .150 20 of an inch and the distance between the upper limit of the groove 21 and the longitudinal central axis of the filament equal to .128 of an inch.

If a still wider focal spot is desired, the distance between the upper limit of the groove 21 is equal 35 to 8.25 millimeters, the depth of the groove is equal to 3.5 millimeters, the width of the slot equal to 4 millimeters and the distance between the upper limit of the groove 21 and the central longitudinal axis of the filament equal to 3.5 millimeters. 40

In all of the above cases the distance between the filament 24 and the center of the target of the anode 12 is about 18 millimeters. Even with spots whose widths and pattern are predetermined, it is necessary to provide a means for controlling the length of said spots. Heretofore small end L-shaped plates have been secured to the cup and located adjacent the filament for this purpose. The position of these plates is 50 critical and a small displacement thereof in the direction of the anode may make an appreciable change in the focal spot length.

In order to obviate said difficulty and so that blurred focal spots may be obviated and so that 55 well defined focal spots may be obtained, in order that the size of the focal spots may be of a predetermined and of a certain size, and so that any quantity of readily reproducible cathode structures adapted to be employed to provide the same 60 size and shaped focal spots on an anode, may be readily manufactured, I have provided the construction illustrated. The filament 24 is of a predetermined length depending upon the length of the desired focal spots as well as upon other 65 factors.

Extending across the groove 21 and perpendicular to the length of the coiled filament are two parallelly spaced short heavy molybdenum, nickel-iron or iron wires or pins 26 and 27. These 70 pins are of circular cross sectional diameter about 40 to 80 mils and are located in openings located in the sides of the cup and adapted to accommodate the same. The pins 26 and 27 have portions thereof respectively in line with a vertical line 75 perpendicular to the horizontal plane of the cup

and passing through the extreme outer coils thereof. The pins 26 and 27 are located vertically adjacent said outer coils but are spaced an appreciable distance therefrom. The vertical distance between the filament and an adjacent pin is of the order of 1 or 2 millimeters. 5

With this construction it is possible to obtain a well defined focal spot on the anode. The focal spot obtained with this construction does not exhibit fanning and feathering at the transverse extremities thereof because of the pins 26 and 27 that are in electrical contact with the cup and, therefore, are at the same potential as the cup and filament 24. These pins may always be mounted in the same spaced relationship by placing the cup in a jig, drilling holes therein and securing pins 26 and 27 in said holes. 10 15

In order to further insure the obviation of any chances of a fanned or feathered focal spot, I provide the shields 28 and 29 composed of rigid 20 sheet metal, such as nickel or the like, which may be suitably cut and otherwise shaped.

The shields 28 and 29 are so cut, shaped and mounted that they are in electrical connection with the cup, whereby the electrons emanating at the cathode 24 may reach the anode only by passing between the pins 26 and 27. The shield 28 has a portion thereof which extends entirely across the slotted open ended lower portion of the cup to form a complete barrier thereacross. Another portion of the shield is bent at right angles to the aforementioned portion, is of substantially rectangular contour and is of such a width that when parallel to the base of the cup it fits rather closely to the sides of the lower portion of the groove 21. This rectangular portion extends from the end of the cup towards the other end thereof and has another portion in the form of a wing which is bent and extends upwardly and towards the pin 26. This last named portion is of such size and contour that its periphery is closely adjacent the sides of the cup defining the groove 21 and the lower portion of the periphery of the pin 26. 30 35 40

The shield 29, which serves the same purpose as the shield 28, has one portion thereof electrically secured by welding to the upper face of the cross piece of the cup defining one end of the slot 23. The other portion of the shield 29 is integral with said first mentioned portion, is bent and extends upwardly towards the pin 27. This last portion is also of wing shape and has its periphery closely adjacent the sides of the cup defining the groove 21 and to the lower portion of the periphery of the pin 27. 45 50 55

The cup 29 has grooves in the sides thereof to accommodate the supports 14 and 15 which are secured thereto by a welding operation. The transverse side of the cup which defines the lengthwise limit of the slot 23 also has a groove 60 therein to accommodate the support and conductor 17 that is electrically and mechanically secured thereto by a welded or other means.

My invention is not to be limited to the specific structure shown because it is susceptible to modifications, but is to be limited only by the prior art. 65

What is claimed:

1. A cathode structure comprising a focusing block and a filament, said focusing block having 70 a groove in one face thereof, said filament being located in said groove, a pin extending across said groove and being secure to said block and said pin being located adjacent one end of the effective length of said filament. 75 75

2. A cathode structure comprising a focusing block and a filament, said focusing block having a groove in one face thereof, said filament being located in said groove, a pin extending across 5 said groove and being secured to said block, said pin being located adjacent one end of the effective length of said filament and a shielding means secured to said block and having a portion thereof extending across said groove to substantially 10 completely fill the cross sectional space of said groove between said filament and said pin.

3. A cathode structure comprising a focusing block and a filament, said focusing block having a groove therein, said filament being located in 15 said groove, a plurality of spaced pins secured to said block, said pins being located between one face of the block and said filament.

4. A cathode structure comprising a focusing block and a filament, said focusing block having a groove therein, said filament being located in 20 said groove, focusing means secured to said block and adjacent said filament, said means including a pair of spaced pins.

5. A cathode structure comprising a focusing block and a filament, said focusing block having a slot extending therethrough and to the upper, lower and one other limiting face of said block, said filament being located in said slot, a pin of 25 curvilinear periphery secured to said block and located above and adjacent said filament, said pin extending across said slot.

6. An X-ray tube comprising an envelope having a press, an anode and a cathode structure therein, a plurality of supporting wires secured 30 to said press, said cathode structure including a focusing block having a slot, said supporting wires secured to said block, a plurality of leading-in conductors sealed in said press and extending interiorly and exteriorly of said envelope, one of 35 said conductors also being secured to said block, a filament mounted in said block and secured to said other conductor, said filament having its other end secured to a support secured to said block, a plurality of pins extending across said 40 slot and secured to said block, shielding means secured to said block and having portions thereof directly across the space adjacent said pins and 45 across said block so that the electrons emanating at the cathode and striking the anode must all 50 pass between said pins.

7. An X-ray tube comprising an envelope having a press, an anode and a cathode structure therein, a plurality of supporting wires secured to said press, said cathode structure including a 55 focusing block having a slot, said supporting wires secured to said block, a plurality of leading-in conductors secured to said press and extending interiorly and exteriorly of said envelope, one of said conductors also being secured to said 60 block, a filament mounted on said block and secured to said other conductor, said filament having its other end electrically connected to said block, a plurality of spaced pins extending across 65 said slot and secured to said block, shielding means secured to said block and extending across

the slot to prevent any substantial quantity of electrons emanating at the cathode from reaching the anode without passing between said pins.

8. A cathode structure comprising a focusing block and a filament, said focusing block having a slot extending therethrough and to the upper, lower and one other limiting face thereof, said filament being located in said slot, focusing pins of curvilinear periphery secured to said block and located above and adjacent said filament, said 10 pins extending across said slot.

9. A cathode structure comprising a focusing block and a filament, said block having a slot extending therethrough and to the upper, lower and one side of the limiting face thereof, said filament being located in said slot, a plurality of pins located above said filament and extending across said slot and secured to said block, said pins and said block serving as a focusing means for electrons that emanate from said filament, the peripheries of said pins being curvilinear. 15

10. An X-ray tube comprising an envelope having a press, electrical conducting means secured to said press, an anode and a cathode structure within said envelope, said means connected to 20 said cathode structure, said cathode structure including a focusing block, said focusing block having a slot extending therethrough and to the upper, lower and one other limiting face thereof, a filament located in said slot, a plurality of spaced 25 pins extending across said slot and secured to said block, shielding means secured to said block and extending across said slot to prevent any substantial quantity of electrons emanating at the filament from reaching the anode without 30 passing between said pins. 35

11. A cathode structure comprising a focusing block and a filament, said block having a slot divided into an upper portion and a lower portion, the upper portion constituting a groove in the 40 upper part of the block and extending from one end of the block to the other end, and the lower portion constituting an aperture in the lower part of the block, said filament being located in said aperture, a plurality of pins of curvilinear 45 periphery secured to said block and extending across the groove in said block adjacent the ends of the filament disposed in said aperture.

12. A cathode structure comprising a focusing block and a filament, said block having a slot divided into an upper portion and a lower portion, the upper portion constituting a groove in the upper part of the block and extending from one end of the block to the other end, and the lower portion constituting an aperture in the 55 lower part of the block, said filament being located in said aperture, a plurality of pins of curvilinear periphery secured to said block and extending across the groove in said block adjacent the ends of the filament disposed in said aperture, shielding means secured to said block and having portions thereof extending across said block to substantially completely fill the cross-sectional space of the groove in said block. 60
